OPERATING SYSTEM FOR VAPOR ARC LAMPS

Lester F. Bird, Newark, N. J., assignor to Hanovia Chemical & Manufacturing Company, Newark, N. J., a corporation of New Jersey

Application October 7, 1947, Serial No. 778,503

2 Claims. (Cl. 315—235)

This invention deals with an operating system for vapor arc lamps and more particularly to operating circuits for metal vapor arc lamps and discharge tubes.

Metal vapor arc lamps and discharge tubes are usually operated from high reactance transformers whereby the secondary reactance limits the current that will flow from the transformer secondary to any resistance load between a short circuit condition and the maximum input of the arc lamp. In the high pressure low voltage arc lamp the voltage drop across the lamp is always low at the time of starting, for instance as low as about 5%—12% of the final operating value, and the effect on the transformer is almost equivalent to a short circuit. It is common practice to design the transformer so that the starting currents are about 1.45 times the usual operating currents and so that during operation the voltage drop across the transformer secondary is the voltage drop across the lamp itself. The reactance of the transformer secondary serves to stabilize the arc lamp and keep it lighted. Such reactance is inductive in character and the current in the lamp circuit lags behind the induced secondary voltage causing a lagging power factor for the supply currents. With such a transformer, the wattage consumed by the lamp varies approximately as the square of the percentage change of line voltage supply, i. e. a 10% change in line voltage results in a 21% change in lamp wattage. Fluctuations in line supply voltages therefore result in wide variations in the light output of the lamp and continuous readjustment of the input connections is required on the transformer if the lamp wattage is to be maintained at or near a constant value. Such variations in light and the consequent adjustments necessary to compensate for these variations are very cumbersome in the operation of such devices.

It is one object of this invention to provide an operating system for vapor arc lamps and discharge tubes, being supplied from alternating current sources, whereby the input to said lamps and discharge tubes, and also the light generated thereby, are rendered less affected by the voltage of the operating supply circuits and are substantially freed from variations resulting from fluctuations in the supply voltage. It is another object of this invention to provide an operating circuit for metal vapor arc lamps and discharge tubes capable of automatically eliminating wide variations in the light output of said lamps and discharge tubes.

Further objects and advantages of this inven-

tion will become apparent from the following description and claims in connection with the accompanying drawings, in which:

Figure 1 is a diagrammatic representation of an operating circuit for metal vapor arc lamps and discharge tubes according to the invention, and

Figures 2, 3, 4 and 5 are graphic representations supplementing the descriptive portion of this invention as indicated therein.

Referring to Figure 1, 1 and 2 are supply lines of variable alternating current voltage from which an enclosed vapor arc lamp is to be operated. A high reactance transformer 3 having a primary 4, a secondary 5 and a leakage reactance 6, such that the secondary short circuit current lies between 1.1 and 1.7 times the normal lamp operating current, is diagrammatically illustrated. The series capacitor 7 has between 1½ and 6 times the kva. rating of the arc lamp 8. Since the arc lamp 8 can only operate in a stable system if it has sufficient series reactance to constitute a complete circuit having a positive volt-ampere characteristic, it must at all times and under all conditions of operation and during all parts of the current cycle have an adequate reactance in series with it to maintain stability. It is inherently impossible to operate with only a series capacitor for the stabilizing means in the circuit 15 of my invention because of an oscillating condition which follows the use of only series capacitive reactance for the stabilization of the arc lamp. I actually utilize a resultant capacitative reactance for stabilization because the capacitor employed is in an effective series connection with an inductive reactance, leaving the sum total, for both, capacitive. The reactance of the series capacitor 7 is chosen to be approximately twice the value of the inductive reactance 6, leaving a resultant capacitative reactance in the circuit essentially equal in value to 6 since in this combination the inductive reactance and the capacitative reactance subtract from each other. Since the resultant reactance is the one which 20 provides stabilization for the lamp, and in this case is capacitative, the lamp is actually operating from a capacitative reactance and so the currents flowing in the secondary or lamp circuit are of leading power factor.

The characteristics of this circuit are radically and essentially different in this combination than would be expected from a simple study of the electrical components, and it has been found that the behavior of the transformer delivering energy 25 to this secondary system is radically altered and

there is not a condition of resonance existing in the secondary circuit since the lamp will not operate if the inductive reactance of 6 and the capacitative reactance of 1 are adjusted to be nearly equal. Such a neutralization results in 10 too low a series stabilizing reactance to permit operation of the arc lamp, as previously stated, and there must always be adequate residual reactance in the circuit. This requirement eliminates any condition of resonance which could exist. However, it has been found that with this 15 circuit, the fluctuations in power consumption of the lamp which occur where the capacitor is omitted, are greatly reduced when the series capacitor of the proper size is added. The value 20 of this capacitor has been found to be about 1½ to 6 times the kva. rating of the lamp. For example, if the wattage of the lamp is 500 watts, the 25 va. of the capacitor is about 1500 or 3 times that of the lamp. Since the same current flows through the capacitor that flows through the lamp, the voltage drop across the capacitor becomes about 3 to 5 times the voltage existing 30 across the lamp.

Since the inductive reactance 6 is most commonly built into the structure of the transformer, and is an electrical rather than a physical entity, it is not possible to show by actual voltage measurements the voltage existing across reactance 6. However, the voltage coming out of 35 the secondary of the reactive transformer, which is a measure of the voltage existing across the series system composed of the capacitance and the lamp, can be measured and is usually found to be approximately equal to the voltage across the capacitor. It has been found that by properly proportioning the coils of the transformer 4 and the ratio of the windings 3 to the winding 5, the secondary circuit is reflected through the transformer to the primary circuit, in such a manner, that the energy in the secondary circuit assumes 40 a condition of high stability, similar to a condition of resonance, and is merely excited by the primary input. The variations in the primary input voltage then no longer appear in equal or greater value in the secondary circuit. Actually, it has been found possible to reduce the fluctuations in the secondary circuit so that they are less than 5% of those in the primary circuit. Moreover, it has been found that the transformer can be so proportioned that the overall reactance existing between the secondary circuit and the primary can be greatly reduced or neutralized by the condensive reactance reflected back through the transformer from the secondary circuit. This substantial neutralization of reactance causes the power factor of the primary current to approach 45 unity although it is always on the leading side.

Therefore, referring to Figure 2, it is found that as the primary voltage is varied from a relatively low value, say 75% of normal, through normal, to possibly 125% of normal, that the input currents to the operating lamp circuit can be made to fall with rising voltage, go through a minimum and again rise. Under other conditions, referring to Figure 3, there is a fall from the start at the 75% of normal value, continuously, up to 125% of normal. Under proper conditions, the input power factor throughout this range can remain substantially constant and relatively high, approximately 80 to 90%. Thus the condition exists where the primary voltage and primary current can be changing rapidly and radically while the secondary currents are remaining substantially constant and unaffected.

The desirable results of my invention are secured fully and are of equal value in the operation of high voltage discharge types of lamps since I have found that the addition of a capacitor of the proper characteristics in series with the discharge tube will produce excellent regulation of the light output essentially independent of the supply line voltages throughout quite wide limits, exceeding in many cases a 25% plus or minus variation from normal. For example, with a high reactance transformer having about 600 volts open circuit secondary volts and adapted to run a 3100 ohm discharge tube at about 110-120 millamps, I add a capacitor in series with the lamps having a reactance of about 5280 ohms at the input frequency and having a voltage drop at about 600 volts to give a va. rating of about 66 voltampères with a lamp rating of about 36. I have found that with this combination of circuit elements, the wattage in the discharge tube varied less than plus or minus 5% while the line voltages varied between about 85% of normal and about 115% of normal. The normal variations in wattage were reduced by the application of my invention to about 8% of those normally to be expected with the usual operating transformers.

The exact electrical interpretation of these results has not been worked out and at the present time is not clearly understood. However, this in no wise reduces the usefulness or practicability of the electrical system. It has been determined, however, that the flux density of the magnetic circuit in the transformer must be at or near the saturation of the iron. If the flux density in the transformer core is not near the knee of the saturation curve, reactions will exist causing variations in current to occur in the secondary circuit, with changes in primary input voltage, that will be much greater than is the case when the flux density is near the saturation point. I, therefore, employ a transformer of such a design that with normal input voltage on the primary, the iron is operating at or near the knee of the saturation curve for the core material. The magnetizing currents flowing in the primary winding vary considerably with changes in the input voltage as does the inductance of the primary as shown in Figure 2.

In Figure 4 is shown a curve illustrating the variations in reactance which are required in series with the arc lamp to accomplish a condition of constant current during variations of the primary voltage, and it will be observed from this curve that on the particular transformer and arc lamp circuit on which this curve was taken that the reactance in series with the arc lamp varied from a value of about 50 ohms with an input voltage of 170 up to 110 ohms at an input voltage of 200 volts and up to 147 ohms at 225 volts and up to 180 ohms at 250 volts. The second of the curves illustrates the actual measurements taken on a transformer to illustrate how closely the actual electrical circuit corresponds with the theoretical reactance required for such a stabilized system. It can be readily seen, therefore, that the stabilization which results from the application of my invention is excellent, and that the advantages of the use of such a system are satisfactory in practical application.

Therefore, my invention accomplishes desirable results in an entirely automatic manner such that variations in the line supply voltage of 10% 75 will not cause a 21% change in the wattage con-

sumption of the lamp, but less than a 5% change in wattage. In most cases, it is possible to have even less than this change, thereby reducing the fluctuations which normally would exist by more than 75%. Referring to Figure 5, I accomplish this desirable result without requiring any manual adjustment, and the results are secured automatically. Moreover, in addition to limiting the variations of power consumption in the arc lamp, I also have altered the power requirements from the supply lines so that a leading power factor is achieved. Such a result is very desirable because of the fact that most electrical equipment involving transformers draws lagging currents from the lines and, therefore, equipment which draws a leading current is generally helpful in stabilizing such voltage fluctuations as are commonly found. All of these desirable results are achieved by the addition of components in accordance with my invention to the usual electrical circuits normally employed with this type of arc lamp.

Moreover, my invention also limits the starting currents flowing to the arc lamp such that a greatly reduced load can be placed on the electrodes of the lamp during the warm up period and so increases the life expectancy and the service secured from the lamp.

What I claim is:

1. A discharge device operating system for maintaining a substantially constant wattage, comprising in combination a transformer having a magnetic core structure and mounted thereon a primary input coil and a secondary inductive coil in spaced relation to each other with a high reluctance magnetic shunt between said coils, a stabilizing wattage circuit comprising a capacitor connected between one of the terminals of said secondary coil and said discharge device, said stabilizing wattage circuit being operative under

5 a series stabilizing reactance provided by the reactance of a secondary coil wound about a core material operating at the knee of the saturation curve for the core material in combination with the reactance provided by a capacitor having a kva. rating of about 1½ to 6 times the kva. rating of said discharge device.

2. An arc lamp operating system for maintaining a substantially constant wattage, comprising in combination a transformer having a magnetic core structure and mounted thereon a primary input coil and a secondary inductive coil in spaced relation to each other with a high reluctance magnetic shunt between said coils, a stabilizing wattage circuit comprising a capacitor connected between one of the terminals of said secondary coil and said discharge device, said stabilizing wattage circuit being operative under a series stabilizing reactance provided by the reactance of a secondary coil wound about a core material operating at the knee of the saturation curve for the core material, so that the secondary current is limited by leakage reactance under short circuit conditions to a value between 1.7 and 1.1 times the normal operating current of the lamp, in combination with the reactance provided by a capacitor having a kva. rating of about 1½ to 6 times the kva. rating of said lamp.
